DISH TOWEL

Simeon Joseph Le Févre, Watertown, Mass.,
assignor to Boott Mills, Lowell, Mass.

Application March 19, 1935, Serial No. 11,873

3 Claims. (Cl. 15—227)

My invention relates to a dish towel.

The essential objects of my invention are to provide, in a manner as hereinafter set forth, a towel of such class for receiving one of the hands and for the passage of the wrist of the user whereby it is detachably connected with the arm of a person when the towel is employed for wiping or other purposes; for coupling it to the wrist of a person if it be desired to employ both hands for purposes other than wiping dishes when occasion requires; to prevent the towel from dropping on the floor when in use; to enable the towel to be hung on the wrist while answering the telephone or doorbell; and to attain these ends in a strong, durable, compact, thoroughly efficient and inexpensive structure.

To the above ends essentially and to others which may hereinafter appear, my invention consists of such parts and such combination of parts which fall within the scope of the invention as claimed.

In the drawing:

Figure 1 is a perspective view of the towel.

Figure 2 is a fragmentary view, in front elevation and upon an enlarged scale, of one end of the towel.

Figure 3 is a section on lines 3—3, Figure 2,

Figure 4 is a section on line 4—4, Figure 2, and Figure 5 is a section on line 5—5, Figure 2.

The towel is formed of two sections 1, 2. The former is set up from a web of fabric of the desired length and width. The section 2 is arranged in superposed relation with respect to section 1 and is formed of a narrow strip of fabric of a length corresponding to the width of said web. The web is so formed and the sections 1, 2 so arranged relatively to each other to provide the towel with a portion 3 to be used for wiping purposes, openings 4, 5 for the selective passage of a wrist and pockets 6, 7 for selectively receiving a hand of the user. The portion 3 is of materially greater length than the length of said openings or the depth of said pockets. The openings 4, 5 align with and are spaced from the mouth of the pockets 6, 7 by the stretch 8 of section 1.

The walls of openings 4, 5 are formed by the stretch 9 of section 1 combined with the section 2 and the spaced parallel rows of stitching 10, 11 and 12. The section 2 is disposed transversely of web 8 and is arranged over stretch 9. The sides of section 2 are secured to sides of the section 1 by the stitching 10, 12. The section 2 at its transverse median is secured to section 1 by

the stitching 11. The latter forms an inner side wall common to said openings.

An end part of section 1 is bent upon itself to provide an oblong fold 13 which opposes the stretch 14 of section 1. The fold 13, stretch 14 and the spaced parallel rows of stitching 15, 16 and 17 form the pockets 6, 7 having their mouths arranged in close parallel relation to the openings 4, 5 respectively. The sides of the fold 13 are secured to sides of the stretch 14 by the rows 10 of stitching 15, 17. The fold 13, as its transverse median, is secured to the stretch 14 by the stitching 16. The latter forms an inner side wall common to said pockets.

The fold 13 is inturned upon itself, as at 18, 15 and the fold and inturned part are secured together, as at 19, for reinforcing the edge 20 of the fold. The section 2 is inturned upon itself, as at 21, and the said inturned parts are secured together, as at 22, for reinforcing the lengthwise edges 23 of section 2. The portion 3 is hemmed as at 24. The openings 4, 5 are arranged at the inner end of the portion 3.

The section 2, in connection with stretch 9, provides a pair of couplers, from either of which the towel may be suspended from the wrist of the user, whether or not the hand extends into one of said pockets. Each pocket forms a hanger means whereby the towel may be suspended or connected to a hand of the user during a wiping operation when employing portion 3. Generally the left wrist will extend through an opening 4 or 5 and the left hand will be positioned in a pocket 6 or 7. The wiping portion 3 will be used by the right hand. When using the towel for wiping dishes an opening 4 or 5 and a pocket 6 or 7 respectively will be employed. It is not necessary when suspending the towel from a wrist to have the hand positioned in a pocket.

What I claim is:

1. A dish towel formed of an elongated oblong web having one of its end terminal portions bent inwardly upon one face thereof to provide a fold disposed transversely of said web from one side to the other thereof, a strip extending transversely of said face from one side edge to the other side edge of the web and arranged in close parallel spaced relation to that edge of the fold disposed transversely of said web, said strip being arranged between the transverse median of the web and the said edge, spaced means for securing said strip at each side and at its transverse median to the web to provide, in connection with the latter, a pair of openings for the selective passage of and for suspending the towel

- from the wrist of a person, and spaced means for securing said fold at each side and at its transverse median to the web to form, in connection with the latter, a pair of pockets for selectively receiving the hand of the person's wrist extended through one of said openings, said pockets having the mouths thereof arranged in parallel spaced relation to the inner ends of said openings.
2. A dish towel comprising a flexible body having a pair of parallel hand receiving pockets at one end terminal portion thereof having their mouths disposed transversely of and located in proximity and inwardly adjacent to an end edge of said body, a strip disposed transversely of said body in proximity to the mouths of said pockets for suspending the towel from the wrist of a person, and means in connection with said strip and body for forming a pair of selective openings for the passage of the wrist of a person and each opposing a mouth of a pocket, that part of said

- 15
- 20

body extending from said strip to the other end of the body forming an elongated portion for wiping dishes.

3. A dish towel comprising an elongated flexible web having side and end edges and an end terminal portion bent thereupon to form a bend and a fold flush with said side edges, spaced parallel means for securing said fold to the body of the web to form a pair of parallel pockets for selectively receiving the hand of a user and having their mouths disposed transversely with respect to the body of the web, the mouths of said pockets being arranged in proximity to and inwardly adjacent said bend, a strip disposed transversely of the web in parallel spaced relation to said mouths, and spaced parallel means for securing the strip to the web to form a pair of parallel wrist receiving openings arranged parallel to the mouths of said pockets.
